UNITED STATES PATENT OFFICE.

WILLIAM H. LOPER, OF BELLGROVE, IDAHO, ASSIGNOR OF ONE-HALF TO
A. A. CRANE, OF HARRISON, IDAHO.

CHAFE-IRON.

No. 795,994

Specification of Letters Patent.

Patented Aug. 1, 1905.

Application filed February 6, 1905. Serial No. 244,429.

To all whom it may concern:

Be it known that I, WILLIAM H. LOPER, a citizen of the United States, residing at Bellgrove, in the county of Kootenai and State of Idaho, have invented new and useful Improvements in Chafe-Irons, of which the following is a specification.

My invention pertains to chafe-irons for use on wagons and other vehicles; and it consists in the peculiar and advantageous construction hereinafter described and claimed.

In the accompanying drawings, forming part of this specification, Figure 1 is a plan view of so much of the running-gear of a wagon as is necessary to illustrate the application of my novel chafe-iron. Fig. 2 is an enlarged detail section taken in the plane indicated by the line 2 2 of Fig. 1 and illustrating the reach or coupling-pole of the running-gear and the antifriction-rollers of my chafe-iron in side elevation. Fig. 3 is a detail transverse section taken in the plane indicated by the line 3 3 of Fig. 2, and Fig. 4 is a detail plan view illustrating the manner in which the antifriction-rollers of a chafe-iron are secured in the body thereof.

Similar letters designate corresponding parts in all of the views of the drawings, referring to which—

A A are the bounds of a running-gear, which are provided with an upper slider B and a lower slider C, the latter being located in a vertical plane in rear of that of the slider B, as clearly shown in Figs. 1 and 2.

D is the reach or coupling-pole of the running-gear, which extends between the two sliders, and E is the chafe-iron constituting the present and preferred embodiment of my invention. The said chafe-iron comprises a sleeve-like body *a*, which is made of cast metal and is of a size to snugly receive the reach or coupling-pole D, an antifriction-roller *b*, journaled in the body *a* and arranged to engage the under side of the upper slider B, and a lower antifriction-roller *c*, journaled in the body and arranged to travel over the upper side of the lower slider C, all as best shown in Fig. 2. The antifriction-rollers *b* and *c* are secured in the body *a* after the manner best shown in Figs. 2 to 4—that is to say, a trunnion *d* at one end of each roller is let into a socket *e* at one end of an oblong opening *f* in the body *a* and a trunnion *g* at the opposite end of the roller is retained in position by

a plate *h*, connected to the body *a* through the medium of a bolt *i*. There are two of the bolts *i* employed, and with their complementary nuts *j* they serve, in addition to connecting the plates *h* to the body *a*, to connect and fix the said body to the reach or coupling-pole D, as shown.

To permit of the bearings of the upper roller *b* being lubricated with facility, I provide a lubricant-duct *k* in the upper side of the body *a* and a lubricant-duct *l* in the upper plate *h*, while for the same purpose with reference to the lower roller *c* I provide lubricant-ducts *m*, Figs. 2 and 3, which extend inwardly and downwardly from one side of the body *a* to the bearings of the said lower roller.

In practice my novel chafe-iron is arranged on and connected to the reach or coupling-pole D and is disposed as shown relative to the upper and lower sliders B and C of the bounds A. In virtue of this arrangement of the chafe-iron and the fact that the antifriction-rollers *b* and *c* are longer than the width of the sliders B and C it will be observed that incident to the movements of the sliders with the bounds the said sliders will bear against the antifriction-rollers and in consequence frictional wear of either the sliders or the reach will be practically prevented. From this it follows that my novel chafe-iron is calculated to materially prolong the usefulness of a running-gear, which is an important desideratum.

The arrangement of the slider B in advance of the slider C and the arrangement of the antifriction-roller *b* in advance of the roller *c* are advantageous for the reason that such arrangements conduce materially to the strength and durability of the structure as a whole.

Notwithstanding the advantages which I have ascribed to my novel chafe-iron in the foregoing description, it will be noted that the chafe-iron is simple and inexpensive in construction and is susceptible of ready application to the reach or coupling-pole of a wagon at present in use, as well as to the reach or coupling-pole of a new wagon.

While I have stated that the body *a* of the chafe-iron is formed of cast metal, I desire it understood that the said body and all of the other parts of the iron may be formed of any suitable material or materials without involving departure from the scope of my invention.

I have entered into a detailed description of the construction and relative arrangement of the parts embraced in the present and preferred embodiment of my invention in order to impart a full, clear, and exact understanding of the same. I do not desire, however, to be understood as confining myself to such specific construction and relative arrangement of parts, as such changes or modifications may be made in practice as fairly fall within the scope of my invention as claimed.

Having described my invention, what I claim, and desire to secure by Letters Patent, is—

In a running-gear, the combination of hounds having upper and lower sliders; one of the said sliders being arranged in a vertical

plane in front of the other, a reach or coupling-pole extending between the said sliders, and a chafe-iron comprising a sleeve-like body surrounding and receiving the reach or coupling-pole and fixedly connected thereto, and upper and lower antifriction-rollers mounted lengthwise in the said sleeve-like body and arranged one in front of the other and in engagement with the said sliders of the hounds.

In testimony whereof I have hereunto set my hand in presence of two subscribing witnesses.

WILLIAM H. LOPER.
